PANTY

Milton R. Anthony and Dorothy Calvacca, New York,
N. Y., assignors to Anthony Costumes, Inc., New York,
N. Y.

Application March 29, 1954, Serial No. 29,728

Term of patent 14 years

(Cl. D3—17)

Fig. 1.

Fig. 2.

To all whom it may concern:

Be it known that we, Milton R. Anthony and Dorothy Calvacca, both citizens of the United States of America and residents of New York city, county of New York, and State of New York, have invented a new, original, and ornamental Design for a Panty, of which the following is a specification, reference being had to the accompanying drawing, forming part thereof, wherein,

We claim:

The ornamental design for a panty, substantially as shown.
